HIGH DENSITY COMPRESS

Application filed February 17, 1930. Serial No. 429,166.

The invention relates to high density compresses and refers more particularly to the side platens of high density compresses and the mechanism for actuating the side platens. 5 One of the objects of the invention is to provide an improved side platen actuating mechanism having a cushioning or relief device through which the actuating force is transmitted. Another object is to provide a 10 cushioning or relief device in the connections between a side platen and a mechanical power device. Further objects of the invention reside in the various features of construction and combinations of parts as more fully 15 hereinafter set forth.

In the drawing:—

Figure 1 is a side elevation, partly broken away, of a high density compress embodying our invention. 20 Figure 2 is a fragmentary horizontal sectional view taken substantially on the line 2—2 of Figure 1.

The high density compress has the base 1 which is formed of the spaced columns 2. 3 is the upper platen of the high density compress mounted upon the base at the upper ends of the columns and having the depending portion 4 which extends between the columns. 5 are tie rods extending transversely through the columns and the depending portion for securing the parts together. 6 is the lower platen of the high density compress below the upper platen and suitably guided by the columns 2 and adapted to be raised and lowered by suitable means (not shown) such as toggle levers, connected to the lower platen and to reduction gearing, which is mounted above and upon the upper platen. 35

40 7 are the side platens which are pivotally mounted at their lower ends upon the columns 2. These side platens are actuated by toggle levers comprising the upper and lower levers 8 and 9, respectively, with the upper levers pivotally connected at 10 to the swinging edges of the side platens and the lower levers pivotally mounted upon the shafts 11 which are spaced outwardly from and extend parallel to the side platens. The levers 8 and 9 are adapted to be in substantial alignment

when the side platens are in closed position.

12 are revoluble gears in axial alignment and driven by corresponding pinions 13, which in turn are driven by suitable reduction gearing. These revoluble gears are located below the lower platen 6 and one is used for actuating one side platen and the other is used for actuating the other side platen, the two being driven together so that the side platens are simultaneously actuated from open to closed positions or vice versa. 55

50 Since the connections between the side platens and their respective actuating revoluble gears are the same, but one will be described. 14 is a link pivotally connected at one end to the revoluble gear 12 and pivotally connected at the other end to the link 15 by a pin which extends transversely through the cross head 16, which is guided by suitable means such as the brackets 17. The construction is such that when the side platen is in closed position the links 14 and 15 are in alignment and the plane passing through the axes of their pivots passes through the axis of the revoluble gear to facilitate holding the toggle levers in operative position maintaining the side platen in closed position. The link 15 is pivotally connected at its other end to the arm 18, which is fixed to the arm 19 and forms therewith a bell crank pivotally mounted upon the shaft 11. The free end of the arm 19 preferably extends beneath the pivotally connected ends of the toggle levers 8 and 9 and is pivotally connected to these pivotally connected ends by the cushioning or relief device 20 which, as shown, comprises the cylinder 21 pivotally mounted upon the free end of the arm 19 and the piston 22 slideable within the cylinder and pivotally connected to the pivotally connected ends of the toggle levers, the cylinder being provided with a suitable inlet port for fluid under pressure, such as compressed air, and this inlet port being at all times in communication with the source of fluid under pressure. 70 75 80 85 90 95

With this construction it will be readily seen that we have provided an improved side platen actuating mechanism comprising a mechanical power device and connections, including a cushioning or relief device between 100

this power device and the side platen whereby sufficient flexibility is provided to protect the parts from breakage or damage. It will also be seen that we have provided, in addition to the cushioning or relief device, a simple construction of actuating mechanism designed to facilitate holding a side platen in closed position.

What we claim as our invention is:

- 10 1. In a high density compress, a side platen and means for actuating the same including toggle levers connected to said side platen, a revolute member, a cushioning device connected to said toggle levers, a pivotal bell crank connected to said cushioning device, and link means between said bell crank and revolute member.
- 15 2. In a high density compress, the combination with a side platen and means for actuating the same including toggle levers comprising a lever pivotally connected to said side platen, and a second lever having a fixed pivot, a revolute member, a cushioning device pivotally connected to said toggle levers, a pivotal bell crank connected to said cushioning device, a link pivotally connected to said bell crank, a second link pivotally connected to said first mentioned link and to said revolute member, and a guide for the connection between said links arranged so that when the toggle levers are in extended position and the side platen is in closed position the plane extending through the axes of the pivotal connections of said second link extends adjacent to the axis of said revolute member.
- 20 3. In a high density compress, a side platen, means for actuating the side platen including toggle levers connected to said platen, a cushioning device connected to said toggle levers, a pivotal bell crank connected to said cushioning device, an actuating member, and link means establishing an operative connection between the bell crank and actuating member.
- 25 4. In a high density compress, a side platen, means for actuating the side platen including levers having their adjacent ends pivotally connected together and having their outer ends respectively pivotally connected to the platen and a fixed support forming a toggle, a cushioning device connected to the toggle at the point of connection between adjacent ends of the levers, a bell crank pivotally connected to the fixed pivot for said toggle and connected to the cushioning device, an actuating member, and means establishing an operative connection between the actuating member and bell crank.

60 In testimony whereof we affix our signatures.

GEORGE W. LANGFORD.
HAROLD L. HAINES.
